UNITED STATES PATENT OFFICE.

WILLIAM T. CLINGER, OF OIL CITY, PENNSYLVANIA.

GAME APPARATUS.

1,257,674.

Specification of Letters Patent. Patented Feb. 26, 1918.

Application filed March 6, 1916. Serial No. 32,482.

To all whom it may concern:

Be it known that I, WILLIAM T. CLINGER, a citizen of the United States, residing at Oil City, in the county of Venango and 5 State of Pennsylvania, have invented certain new and useful Improvements in Game Apparatus; and I do hereby declare the following to be a full, clear, and exact description of the invention, such as will enable 10 others skilled in the art to which it appertains to make and use the same.

This invention relates to improvements in game apparatus, and more particularly to such apparatus as is designed for the employment of articles intended for aerial projection.

The primary object in view is the testing of the skill of the player by limiting the path of travel of the projectile and requiring the 20 direction of the projectile along such restricted path for the successful playing of the game.

With this and further objects in view, as will in part hereinafter become apparent 25 and in part be stated, the invention comprises certain novel constructions, combinations and arrangements of parts as subsequently specified and claimed.

In the accompanying drawing,

30 Figure 1 is a perspective view of an apparatus embodying the features of the present invention.

Fig. 2 is a plan view of the casing detached from its supporting frame.

35 Fig. 3 is a detail, fragmentary, vertical section through the lower portion of the casing.

Referring to the drawing by numerals, 1, 1 indicate the bars and upright frame 40 designed to support a casing 2. The casing 2 is a hollow, tubular member of any appropriate material, such as papier-mâché or fabric, or the like, and may have any contour consistent with the functions herein- 45 after attributed to it, but preferably is formed conical or frusto-conical, tapering downward. The upper end or base of the cone is bounded by a ring 3, preferably of metal, for giving stability to the casing, and 50 at diametrically opposite points the ring is provided with trunnions 4', 4', outstanding and finding bearings in the upper end portions of bars 1. The upper end of the casing 2 is provided with a closure or cover 4 55 formed of fabric or other appropriate ma-

terial and provided centrally with an opening 5. The opening 5 is constructed to be variable in dimension, and the variation may be obtained in any of numerous ways, one simple method being indicated consisting of 60 having the central portion of the cover 4 formed of netting and a draw-string passed through certain portions of the mesh and tied to form the border of the opening 5. To increase the size of the opening it is only 65 necessary to turn back more of the netting and lace the draw-string through outer portions thereof. Converse operation will provide the reduction in the size of the opening 5 when it is desired to reduce the same. 70

The lower end of the casing 2 is closed by a cover 7 formed with an aperture 8 through which is destined to extend a portion of the football or other like projectile 9. The football 9 is of a diameter less than that of the 75 smaller end of the casing 2 and less than the diameter of the opening 5, so that said ball can be projected axially of the casing 2 and through the opening 5. It will now be clear that the opening 5 may be varied 80 in diameter, either according to the skill of the player or consistent with different sizes of balls 9. The bottom closure 7 is of fabric or other flexible material, and a part of the lower end portion of casing 2 is also of flexible material, as indicated at 10, so as to avoid liability of injury to the operator when kicking the ball in the event that he strikes the casing instead of the ball, or in addition to striking the ball. 85

The casing 2 may be caused to assume any location relative to the horizon, but, as seen in Fig. 1, is preferably inclined and is held in the inclined position by appropriate stays 11 attached near the lower end, and a co- 90 operating stay 12 attached at or near the upper end of the casing. To prevent collapse of the flexible portion 10 of the casing, a stay 13 is connected at the extreme lower portion thereof and extended to the 95 stay 12 in position for sustaining the portion 10 of casing 1 in proper alinement with the rest of the casing. Of course, when the casing 2 is used in a vertical position the stays 11, 12 and 13 will not be required. 100

The frame 1 may be retained in position by any appropriate securing means, as, for example, guy lines 14, 14.

The operation of the structure it is believed will be apparent from the descrip- 110

tion, and consists briefly in depositing a football in the casing 2 and locating it in the aperture 8 so as to be accessible to the foot of the player. The object of the player 5 is to kick the ball with such force and accuracy as to drive it through the opening 5. The scores and rules may be varied at the pleasure of the player.

It is obvious, of course, that the casing 2 10 may vary in size and proportions, but should be of such length as to require some little practice and skill in the driving of the ball from the aperture 8 through the aperture 5. A casing 2 ten or twelve feet in length will 15 provide means for amusement and practice, and after a player has become very proficient he will probably find it desirable to use casings of greater length.

What I claim is:—

20 1. In a game apparatus, a hollow casing having a closure at one end formed with an opening through which a football is adapted to be projected from within the casing, and means for sustaining a football adjacent the opposite end of the casing in position for being accessible to the foot of a player.

25 2. In a game apparatus, a hollow casing having a closure at one end formed with an opening through which a football is adapted to be projected from within the casing, and a flexible support for a football at the other end of the casing.

30 3. In a game apparatus, a hollow casing, a closure therefor having an opening through 35 which a projectile is adapted to move when moving longitudinally of and within the

casing, and a support for a projectile at the opposite end of the casing.

4. In a game apparatus, a hollow casing, a closure therefor having an opening through 40 which a projectile is adapted to move when moving longitudinally of and within the casing, and a flexible support for a projectile at the opposite end.

5. In a game apparatus, the combination 45 with a frame, of a conical casing sustained thereby with its larger end upward, a cover for the larger end of the casing having an opening through which a projectile moving longitudinally of the casing is adapted to 50 pass, and means at the lower end of the casing for supporting a projectile in position for being struck so as to be projected longitudinally of the casing.

6. In a game apparatus, the combination 55 with a frame, of a conical casing sustained thereby with its larger end upward, a cover for the larger end of the casing having an opening through which a projectile moving longitudinally of the casing is adapted to 60 pass, means at the lower end of the casing for supporting a projectile in position for being struck so as to be projected longitudinally of the casing, and means for sustaining the casing in an inclined position. 65

In testimony whereof I affix my signature in presence of two witnesses.

WILLIAM T. CLINGER.
